UNITED STATES PATENT OFFICE.

HENRY LEITHNER, OF SAN FRANCISCO, CALIFORNIA.

AUXILIARY AIR-VALVE.

1,359,079.

Specification of Letters Patent. Patented Nov. 16, 1920.

Application filed March 5, 1919. Serial No. 280,759.

To all whom it may concern:

Be it known that I, HENRY LEITHNER, a citizen of the United States, residing at San Francisco, in the county of San Francisco and State of California, have invented new and useful Improvements in Auxiliary Air-Valves, of which the following is a specification.

This invention relates to an internal combustion engine and particularly pertains to an auxiliary air device therefor.

It is the principal object of this invention to provide means whereby a continuous supply of heated air may be delivered to the intake manifold of an internal-combustion engine and united with the gaseous fuel passing from the carburetor, thus warming the resultant gas and making it more volatile when ignited.

It is another object of this invention to devise an auxiliary air device which may be readily used for priming an engine or for delivering suitable vapor to the engine cylinders when carbon is to be destroyed therein.

The invention contemplates the use of a control valve adapted to be actuated from the dashboard of a vehicle and which will regulate the inflow of air to an engine manifold from a flexible air tube, said tube being detachably secured within a heating casing, which casing in turn is secured directly upon the exhaust manifold of the engine.

The invention is illustrated by way of example in the accompanying drawings, in which—

Figure 1 is a view in side elevation, illustrating the application of the invention and further disclosing, by dotted lines, the manner in which the engine may be primed or cleaned.

Fig. 2 is a view in elevation, illustrating the air inlet valve.

Fig. 3 is a view in central horizontal section through the air inlet valve, connected with the manifold.

Referring more particularly to the drawings, 10 indicates the air valve connected to a controlling lever 11 by a control cable 12 at one end. The control lever is suitably pivoted upon a quadrant 14 of a vehicle. It will be understood that the lever will be adjustably set as desired, in relation to this quadrant. The opposite end of the valve structure 10 is fastened to a flexible metallic

tube 15. This tube is led to a casing member 16 which is here shown as fixed by straps 17 to the exhaust manifold 18 of the engine 19. The tube 15 extends through the casing member 16 and is there provided with a clamping collar 20. Due to this arrangement, the tube is detachably held in position through the case and may be readily removed for purposes hereinafter set forth. The case 16 is preferably formed of some metal having high heat conducting properties such as copper, and will thus cause a radiation of heat so that air passing inwardly through the open end of the tube 15 will be heated as it flows to the valve structure 10.

Reference being had to Fig. 3, it will be noted that the valve structure 10 is formed with a cylindrical and tubular case 21, at one side of which a connecting tube 22 is formed. These two members are preferably cast integrally and communicate with each other through a passageway 23. The connecting member 22 is externally threaded and extends through a threaded opening 24 in the intake manifold 24 of the engine. The end of the passageway 23 is closed. However, a plurality of radial ducts 25 are formed through the side wall of the member 22 near the end of the passageway and thus distribute the inflowing air to the gaseous mixture flowing from the carburetor 26 to the engine 19. Mounted within the tubular casing 21 is a piston valve 27. This valve normally closes the passageway 23 and is held in this closing position by an expansion spring 28. One end of the expansion spring extends into a counter-bore at the back of the valve member 27 while the other end rests against a threaded plug 29 mounted within the open end of the casing 21. This plug also forms a connection for the flexible tube 15. The head of the valve member 27 is formed with a plurality of perforations 30, through which air may pass from tube 15 and thereafter flow into the passageway 23 as the valve member 27 uncovers the inflow end of this passageway. Actuation of the valve is produced by movement of the cable 12 as directly effected by the swinging of the control lever 11.

In operation of the present invention, it will be understood that the valve structure 10 is mounted in the manifold, as particularly shown in Fig. 3, and the tube 15 held

in place within the casing 16 by means of the clamping collar 20 or some other quickly detachable fastener. When the engine is set in motion, the heat of the exhaust gases 5 will immediately warm the exhaust manifold 18 and will thereafter be absorbed by the casing 16. This gas will be radiated to the metal pipe 15. Due to the fact that this pipe is completely formed of metal, al- 10 though flexible, it will be readily heated throughout its length and will thus quickly warm the air drawn in through its open end and delivered to the valve casing.

By opening the valve, this air will pass 15 into the manifold and thereafter pass out in small streams into the gas flowing to the engine. In the event that the engine is cold and will not readily start, the flexible tube 15 may be withdrawn from the casing 16 20 and inserted within a bottle of gasolene. When the engine is turned over, this will act to draw gasolene directly into the manifold above the carbureter 26 and thus enrich the mixture so that an explosion will 25 take place within the engine cylinders.

After the engine has been satisfactorily started, the tube 15 may be re-inserted through the casing 16 and there locked. When the engine cylinders have accumu- 30 lated an objectionable amount of carbon, this may be readily removed by withdrawing the tube 15 from its casing and submerging its open end within a container 31. This container may be filled with benzin, 35 alcohol or some other solution which will readily destroy the carbon within the cylinders as the engine runs.

It will thus be seen that the device here disclosed may be readily converted to meet 40 various requirements of the engine and to insure that it will run more perfectly and may be maintained in proper working condition. It will further be noted that the structure is of simple construction and so

designed as to be readily applied to an en- 45 gine.

Having thus described my invention, what I claim and desire to secure by Letters Patent is—

1. In combination with the exhaust and intake manifolds of an engine, and a carbureter, an auxiliary air valve casing connected to the intake manifold, a heat casing borne by the exhaust manifold, a metal tube associated with the heat casing and secured at one end to the valve casing, a hollow slidable valve in the casing having ports in one end, a coil spring in the valve casing extending in the valve interior and disposed between the inner end of the valve 60 and the end of the valve casing adjacent said tube and having its hollow center communicating with the ports and the end of the tube affixed to the valve casing, and slidable means operating in the valve cas- 65 ing and abutting the opposite end of the valve to unseat the latter.

2. In combination with the exhaust and intake manifolds of an engine and a carbureter, an auxiliary air valve casing connected to the intake manifold and having a passageway communicating therewith, a heat casing borne by the exhaust manifold, a metal tube associated with the heat casing and secured at one end to the valve cas- 70 ing, a valve slidable in the casing and having ports, a spring in the valve casing for holding the valve in a position to close said passageway, and means to unseat the valve thereby to open said passageway so that the 75 valve ports can communicate therewith.

In testimony whereof I have hereunto set my hand in the presence of two subscribing witnesses.

HENRY LEITHNER.
